CONVERSION OF HYDROCARBON OILS

Jacque C. Morrell, Chicago, Ill., assignor to Universal Oil Products Company, Chicago, Ill., a corporation of Delaware

Application September 28, 1934, Serial No. 745,875

16 Claims. (Cl. 196—48)

This invention particularly refers to an improved process for the fractional distillation of hydrocarbon oils of relatively wide boiling range, such as crude petroleum, for example, accompanied by the pyrolytic conversion, under independently controlled conditions, of relatively low-boiling and high-boiling fractions of the charging stock from the topping operation as well as selective further conversion, within the same system, of relatively low-boiling and high-boiling intermediate products of the process.

The present invention offers a unified system of simple form for the simultaneous conversion of selected relatively low-boiling and high-boiling fractions of the charging stock together, respectively, with selected relatively low-boiling and high-boiling fractions of the insufficiently converted intermediate products of the process, said relatively low-boiling and high-boiling fractions each being subjected to the conditions of treatment particularly suited for the conversion of each to produce maximum yields of good quality motor fuel.

As a special feature of the present invention the overhead vaporous products from the topping operation are preferably subjected, together with low-boiling insufficiently converted intermediate products of the cracking operation, to conversion or reforming in a heating coil at relatively high temperature conversion conditions and preferably the overhead products from the topping operation are supplied to this heating coil while still in vaporous state without being first subjected to condensation, which would result in considerable loss of heat, in order to obviate the use of a vapor pump to pass the hot vaporous products from the topping operation through said heating coil. The topping operation is preferably conducted at a sufficiently higher pressure than that employed in the heating coil to overcome the drop in pressure, due to friction, through the heating coil and succeeding portions of the equipment.

As another special feature of the present invention, conversion of the highly heated relatively low-boiling materials from the high-temperature heating coil is preferably arrested or retarded to a degree sufficient to prevent their excessive further conversion by cooling the same by indirect contact with charging stock for the process, which is thereby furnished heat to effect or assist its fractional distillation, and/or by direct contact with the relatively cool higher boiling oils, such as selected relatively high-boiling products from the topping operation and/or selected relatively high-boiling insufficiently converted intermediate

products of the cracking operation, whereby heat is furnished to said relatively high-boiling oils to effect or assist their conversion at a milder temperature than that to which the relatively low-boiling oils are subjected.

One specific embodiment of the present invention may comprise subjecting hydrocarbon oil charging stock for the process, comprising an oil of relatively wide boiling range, to fractional distillation at substantial superatmospheric pressure, whereby it is separated into relatively low-boiling fractions, comprising the overhead vaporous products, and relatively high-boiling fractions, comprising condensate or bottoms from the distilling operation, subjecting said low-boiling vaporous fractions to conversion conditions of elevated temperature and superatmospheric pressure in the heating coil, introducing the stream of highly heated products from said heating coil into an enlarged reaction chamber, also maintained at superatmospheric pressure, and commingling therewith said high-boiling fractions of the charging stock, withdrawing both vaporous and liquid conversion products from the reaction chamber, subjecting the latter to further vaporization at substantially reduced pressure, subjecting the vaporous conversion products, including those resulting from said further vaporization, to fractionation in a separate fractionating zone, whereby their insufficiently converted components are condensed as reflux condensate and separated into selected relatively low-boiling and high-boiling fractions, subjecting fractionated vapors of the desired end-boiling point from said separate fractionating zone to condensation, collecting and separating the resulting distillate and gas, returning said relatively low-boiling fractions of the reflux condensate to the heating coil for further conversion, together with the low-boiling vaporous fractions of the charging stock, and returning the relatively high-boiling fractions of the reflux condensate to the reaction chamber for further conversion.

As an alternative method of operation, which however, is not equivalent to the method above described, either the high-boiling fractions of the charging stock or the high-boiling fractions of the reflux condensate or both may, when desired, be subjected in a separate heating coil to milder conversion conditions than those to which the low-boiling fraction of the charging stock and low-boiling reflux condensate are subjected, prior to the introduction of said high-boiling fractions into the reaction chamber. In such cases the stream of heated products from the

high temperature heating coil to which the relatively low-boiling oils are supplied will not be cooled upon commingling with the higher boiling oils to such an extent as when neither of said 5 high-boiling oils are subjected to conversion in a separate heating coil. It may, therefore, be desirable to partially cool the stream of highly heated products from the high-temperature light oil heating coil, prior to its introduction into the 10 reaction chamber in order to retard conversion of these products sufficiently to prevent excessive further conversion in the reaction chamber. The present invention provides for cooling of the stream of heated products from the high-temperature 15 light oil heating coil by indirectly contacting a regulated portion or all of said stream with the hydrocarbon oil charging stock for the process which is subsequently supplied to the fractional distilling stage, thereby furnishing a 20 portion or all of the heat required for said fractional distillation of the charging stock.

It will be noted that the various features of the invention are cooperative and mutually contribute to produce the desired final results. The 25 invention is, however, not limited to the use of all of the various features herein described in a single operation and alternative methods of operation are not to be considered equivalent.

The accompanying diagrammatic drawing 30 illustrates one specific form of apparatus for carrying out the invention. A description of the operation of the process of the invention, as it may be accomplished in an apparatus such as illustrated, is included in the following description of 35 the drawing. Hydrocarbon oil charging stock for the process, preferably comprising an oil of relatively wide boiling range containing an appreciable quantity of both relatively low-boiling and relatively high-boiling components, such as crude 40 petroleum, for example, is supplied through line 1 and valve 2 to pump 3 wherefrom it may be fed through line 4, valve 5, heat exchanger 6, line 7 and valve 8 into distilling column 9, entering this zone in substantially vaporized state and being 45 subjected therein to fractional distillation. In the particular case here illustrated the heat required for fractional distillation of the charging stock may be supplied thereto in heat exchanger 6 by indirect contact and heat exchange between 50 the charging stock and highly heated conversion products of the process, which are supplied to this zone as will be later more fully described. It is, however, also within the scope of the present invention to employ a heating coil of any 55 conventional form for the charging stock or to impart thereto all or a portion of the heat required for its fractional distillation in any other well known manner, not illustrated.

Distilling column 9 is preferably operated at a 60 substantial superatmospheric pressure in order to eliminate pumping of the overhead vaporous products from this zone supplied to the cracking coil. In the case here illustrated, the charging stock is separated by fractional distillation in 65 column 9 into a selected overhead vaporous product of the desired end-boiling point and bottoms, which latter comprise components of the charging stock remaining unvaporized in column 9 as well as the components which are condensed in 70 this zone as reflux condensate. It is, of course, also within the scope of the invention, particularly in case the charging stock contains any desirable low-boiling, intermediate or high-boiling fractions which it is not desired to subject to 75 conversion, to separate the charging stock into

more than two selected fractions and to withdraw said desirable components such as, for example, straight-run gasoline of good antiknock value, lubricating oil, asphaltic material, etc., from the system by well known means, not illustrated in 5 the drawing.

The selected low-boiling components of the charging stock remaining unvaporized in column 9 are withdrawn, in the case here illustrated, from the upper portion of this zone through line 10 10 to be supplied therefrom through valve 11 to conversion or reforming in heating coil 12.

When desired, a regulated portion of the overhead vaporous product from column 9 may be subjected to condensation, by well known means 15 not illustrated, for the purpose of forming distillate which may be utilized as a refluxing medium in column 9 by recirculating said distillate to the upper portion of this zone, by well known means not illustrated. This is only one of the 20 many well known satisfactory methods which may be employed for assisting fractionation in column 9 and maintaining the desired vapor outlet temperature from this zone so as to control the end-boiling point of the materials subjected 25 to conversion in heating coil 12.

Heating coil 12 is located within a furnace 13 of any suitable form by means of which the heat required for accomplishing the desired conversion of the low-boiling components of the charging stock is supplied thereto. Heating coil 12 is also preferably operated at a substantial superatmospheric pressure and the highly heated products are discharged from this zone through line 14 and may be directed, all or in part, 30 through valve 15 in this line and through heat exchanger 6, line 16 and valve 17 into reaction chamber 20. The highly heated products from heating coil 12 passed, as illustrated, through heat exchanger 6 serve to supply to the charging stock all or a portion of the heat required 35 for its fractional distillation. When desired, all or a regulated portion of the stream of hot vaporous products from heating coil 12 may bypass heat exchanger 6 by diverting the same from line 14 through line 18 and valve 19 into line 16 and thence to reaction chamber 20.

In case all or a substantial portion of the highly heated products from heating coil 12 are passed through heat exchanger 6 they will be cooled 50 sufficiently by indirect contact with the charging stock in this zone to materially retard or arrest their further conversion, in which case a regulated portion or all of one or both of the other oils supplied to reaction chamber 20, which other oils comprising high-boiling fractions of the charging stock and high-boiling fractions of the insufficiently converted intermediate products of the process (reflux condensate, are preferably subjected to conversion in heating coil 33, 55 prior to their introduction into the reaction chamber.

In case only a minor portion or none of the highly heated products from heating coil 12 are passed through heat exchanger 6 to be cooled 60 by indirect contact with the charging stock the heat contained in these products may be utilized to effect or assist conversion of a portion or all of either or both of the relatively high-boiling oils supplied to reaction chamber 20 as will be later more fully described, in which case said high-boiling oils serve to cool the highly heated products from heating coil 12 sufficiently to prevent their excessive further conversion in reaction chamber 20.

In the case here illustrated the high-boiling fractions of the charging stock withdrawn from the lower portion of column 9 through line 21 and valve 22 to pump 23 are fed therefrom 5 through line 24 and may be introduced, all or in part, into reaction chamber 20 through line 25 and valve 26 or a regulated portion or all of this material may pass through valve 27 in line 24 into line 31 and thence to heating coil 33. 10 High-boiling fractions of the reflux condensate produced in fractionator 46, as will be later more fully described, which reflux condensate comprises the insufficiently converted intermediate products of the process are withdrawn from the 15 lower portion of the fractionator through line 28 and valve 29 to pump 30 by means of which they are fed through line 31 and may pass, all or in part, through valve 32 in this line to conversion in heating coil 33 or a regulated portion or 20 all of this material may be supplied from line 31 through line 34 and valve 35 to reaction chamber 20.

Heating coil 33, when employed, is preferably operated at a substantial superatmospheric pressure and the oil supplied to this zone is heated by means of heat supplied from a furnace 36 of any suitable form to the desired conversion temperature which is preferably less than that employed at the outlet from heating coil 12. The heated 30 products are discharged from heating coil 33 through line 37 and valve 38 and, in the case here illustrated, are directed through line 16 into reaction chamber 20.

Reaction chamber 20 is preferably also operated at a substantial superatmospheric pressure. It will be understood, of course, that any or all of the various oils supplied to this zone may be separately introduced thereto by well known means, not shown in the drawing, instead of being commingled, as illustrated, prior to their introduction into the reaction chamber. In any case the relatively high-boiling oils supplied to chamber 20 and particularly their vaporous components are subjected to appreciable conversion 45 in this zone by virtue of the temperature and pressure conditions maintained therein, the heat required for such conversion being derived either from the heated products from heating coil 12 or supplied by means of heating coil 33 or from both 50 sources. In the particular case here illustrated, both vaporous and liquid conversion products are withdrawn from the lower portion of chamber 20 through line 39 and valve 40 and are introduced into vaporizing chamber 41. It will be understood, however, that, when desired, all or a regulated 55 portion of the vaporous products may be separately withdrawn from chamber 20 at any desired point in this zone, by well known means not illustrated, in which case the separately withdrawn vapors may be supplied, all or in part, directly to fractionator 46 or may be introduced, all or in part, into vaporizing chamber 41 at any desired point in this zone, by well known means not shown in the drawing.

Chamber 41 is preferably operated at a substantially reduced pressure relative to that employed in the reaction chamber by means of which further vaporization of the liquid conversion products supplied to this zone from reaction 70 chamber 20 is accomplished. Residual liquid remaining unvaporized in chamber 41 may be withdrawn from the lower portion of this zone through line 42 and valve 43 to cooling and storage or to any desired further treatment. The vaporous products evolved in chamber 41 as well

as any supplied to this zone from the reaction chamber may be directed through line 44 and valve 45 to fractionation in fractionator 46, together with any vaporous products which may be supplied, as previously mentioned, to fractionator 46 direct from reaction chamber 20. 5

The components of the vaporous products supplied to fractionator 46, including their fractions boiling above the range of the desired final light distillate product of the process as well as, 10 when desired, regulated quantities of selected high-boiling fractions within the boiling range of the desired light distillate product but of inferior anti-knock value, are condensed in this zone as reflux condensate and, in accordance 15 with the features of the present invention, are separated into selected relatively low-boiling and high-boiling fractions. The high-boiling fractions of the reflux condensate may be returned, as already described, to heating coil 33 or to reaction chamber 20 or, in part, to both for further conversion. The selected relatively low-boiling fractions of the reflux condensate may be withdrawn from any suitable intermediate point 20 or plurality of points in the fractionator and, in 25 the particular case here illustrated, are withdrawn therefrom through line 47 and valve 48 to pump 49 by means of which they are returned through line 50 and valve 51 to further conversion 30 in heating coil 12, together with the low-boiling fractions of the charging stock.

Fractionated vapors of the desired end-boiling point, preferably comprising materials within the boiling range of motor fuel of good antiknock value are withdrawn, together with uncondensable gas produced by the cracking operation from the upper portion of fractionator 46 through line 52 and valve 53 to be subjected to condensation and cooling in condenser 54. The resulting distillate and gas passes through line 40 55 and valve 56 to collection and separation in receiver 57. Uncondensable gas may be released from the receiver through line 58 and valve 59 to absorption, storage or elsewhere, as desired. The distillate collected in receiver 57 may be withdrawn therefrom through line 60 and valve 61 to storage or to any desired further treatment. When desired, a regulated portion of the distillate collected in receiver 57 may be recirculated by well known means, not illustrated 50 in the drawing, to the upper portion of fractionator 46 to serve as a refluxing and cooling medium in this zone to assist fractionation of the vapors and to maintain the desired vapor outlet temperature from the fractionator. 55

In a process of the character illustrated and above described, the preferred range of operating conditions may be approximately as follows: The temperature to which the charging stock is subjected for the purpose of effecting its fractional distillation may range, for example, from 500 to 800° F., or thereabouts, depending upon its characteristics, the desired separation to be effected and upon the pressure employed in the fractional distilling stage of the process, which pressure may range, for example, from 100 to 500 pounds, or thereabouts, per square inch. The conversion temperature employed at the outlet from the heating coil to which the low-boiling fractions of the charging stock and the selected 60 low-boiling fractions of the reflux condensate are supplied may range, for example, from 900 to 1100° F. and preferably a substantial superatmospheric pressure of the order of 200 to 500 pounds, or more, per square inch, is employed at 65 70 75

this point of the system although, when desired, lower pressures down to 100 pounds, or less, per square inch, may be employed in this zone. When a separate heating coil is employed for conversion of high-boiling fractions of the charging stock or high-boiling fractions of the reflux condensate or both, the conversion temperature employed at the outlet from this zone may range, for example, from 800 to 950° F., or thereabouts, 10 and preferably a superatmospheric pressure of the order of 100 to 500 pounds, or thereabouts, per square inch, is employed at the outlet from this heating coil. The reaction chamber is preferably operated at a substantial superatmospheric pressure of the order of 100 to 500 pounds, 15 per square inch, which pressure may be substantially the same or somewhat less than the pressure employed in the light oil heating coil or in the heavy oil heating coil, in case the latter zone 20 is employed and is operated at a lower pressure than that employed in the light oil coil. The vaporizing chamber is preferably operated at a substantially reduced pressure relative to that employed in the reaction chamber which may 25 range, for example, from substantially atmospheric pressure to 100 pounds, or thereabouts, per square inch superatmospheric. The pressure employed in the vaporizing chamber may be substantially equalized or somewhat reduced in 30 the succeeding fractionating, condensing and collecting portions of the system.

As a specific example of one of the many possible operations of the process of the present invention, as it may be accomplished in an apparatus such as illustrated and above described, the charging stock comprises a California crude of about 33° A.P.I. gravity containing approximately 34 percent of material boiling up to 437° F. and containing no appreciable amount of light ends 35 boiling below 198° F. This material is heated to a temperature of approximately 700° F. by indirect contact and heat exchange with the stream of highly heated products from the light oil heating coil of the system and is subjected to fractional distillation at a superatmospheric pressure of about 250 pounds per square inch. The low-boiling fractions of the charging stock, comprising its components boiling up to approximately 550° F. are subjected, together with low-boiling fractions of the reflux condensate, 40 comprising intermediate products of the cracking operation having a boiling range of approximately 350 to 600° F., are subjected in the light oil heating coil of the system to an outlet conversion temperature of approximately 1000° F. with a superatmospheric pressure in this zone substantially equalized with that in the fractional distilling stage of the process. The high-boiling fractions, comprising about 42 percent, or thereabouts, of 45 the charging stock, are subjected in a separate heating coil to an outlet conversion temperature of approximately 950° F. at a superatmospheric pressure of about 200 pounds per square inch and the heated products from this coil as well as the 50 partially cooled products from the light oil heating coil which, however, are still at a temperature appreciably within the conversion range are introduced into the reaction chamber. High-boiling fractions of the reflux condensate from the 55 fractionator of the cracking stage are also returned to the reaction chamber to commingle with the heated products from the two heating coils and be subjected to further conversion therewith. The reaction chamber is maintained at a superatmospheric pressure substantially equal- 60

ized with that at the outlet from the light oil heating coil.

The vaporizing chamber is operated at a reduced pressure of approximately 50 pounds, per square inch, superatmospheric, and this pressure is substantially equalized in the succeeding fractionating, condensing and collecting portions of the system. This operation will produce, per barrel of charging stock, approximately 72 percent 5 of 400° F. end-point motor fuel having an octane 10 number of approximately 70 by the motor method and approximately 15 percent of good quality residual liquid meeting specifications for premium fuel oil, the remainder being chargeable, principally, to rich uncondensable gas. 15

I claim as my invention:

1. A process for the fractional distillation and selective conversion of hydrocarbon oils which comprises subjecting hydrocarbon oil of relatively wide boiling range to fractional distillation at 20 substantial superatmospheric pressure whereby it is separated into selected relatively low-boiling and high-boiling fractions, withdrawing said low-boiling fractions from the fractional distilling stage in vaporous state and supplying the same 25 without intentional condensation thereof to a heating coil, wherein they are subjected to conversion conditions of elevated temperature and superatmospheric pressure, introducing the products from said heating coil into an enlarged reaction chamber also maintained at superatmospheric pressure and at a conversion temperature, introducing said selected high-boiling fractions of the charging stock into said reaction chamber wherein they are subjected to conversion, withdrawing vaporous and liquid conversion products from the reaction chamber, subjecting the vaporous conversion products of the process to 30 fractionation, whereby their insufficiently converted components are condensed as reflux condensate and separated into selected relatively low-boiling and high-boiling fractions, subjecting fractionated vapors of the desired end-boiling point to condensation, collecting the resulting distillate, returning said selected low-boiling fractions of 35 the reflux condensate to the heating coil for further conversion, together with said low-boiling fractions of the charging stock, and returning said high-boiling fractions of the reflux condensate to the reaction chamber for further conversion. 40

2. A process for the fractional distillation and selective conversion of hydrocarbon oils which comprises subjecting hydrocarbon oil of relatively wide boiling range to fractional distillation at 55 substantial superatmospheric pressure whereby it is separated into selected relatively low-boiling and high-boiling fractions, withdrawing said low-boiling fractions from the fractional distilling stage in vaporous state and supplying the same, without intentional condensation thereof, to a heating coil wherein they are subjected to conversion conditions of elevated temperature and superatmospheric pressure, introducing the products from said heating coil into an enlarged 60 reaction chamber also maintained at superatmospheric pressure and at a conversion temperature, introducing said selected high-boiling fractions of the charging stock into said reaction chamber wherein they are subjected to conversion, withdrawing vaporous and liquid conversion products from the reaction chamber, subjecting the latter to further vaporization at substantially reduced pressure, subjecting the vaporous conversion products of the process to 65 fractionation, whereby their insufficiently converted components are condensed as reflux condensate and separated into selected relatively low-boiling and high-boiling fractions, subjecting fractionated vapors of the desired end-boiling point to condensation, collecting the resulting distillate, returning said selected low-boiling fractions of 70 the reflux condensate to the heating coil for further conversion, together with said low-boiling fractions of the charging stock, and returning said high-boiling fractions of the reflux condensate to the reaction chamber for further conversion. 75

tionation, whereby their insufficiently converted components are condensed as reflux condensate and separated into selected relatively low-boiling and high-boiling fractions, subjecting fractionated vapors of the desired end-boiling point to condensation, collecting the resulting distillate, returning said selected low-boiling fractions of the reflux condensate to the heating coil for further conversion, together with said low-boiling fractions of the charging stock, subjecting said high-boiling fractions of the reflux condensate to independently controlled conversion conditions of elevated temperature and superatmospheric pressure in a separate heating coil 15 and introducing the resulting heated products into said reaction chamber.

3. A process for the fractional distillation and selective conversion of hydrocarbon oils which comprises subjecting hydrocarbon oil of relatively wide boiling range to fractional distillation at substantial superatmospheric pressure, whereby it is separated into selected relatively low-boiling and high-boiling fractions, withdrawing said low-boiling fractions from the fractional 20 distilling stage in vaporous state and supplying the same without intentional condensation thereof to a heating coil wherein they are subjected to conversion conditions of elevated temperature and superatmospheric pressure, introducing the products from said heating coil into an enlarged reaction chamber also maintained at superatmospheric pressure and at a conversion temperature, withdrawing vaporous and liquid conversion products from the reaction chamber, subjecting the latter to further vaporization at substantially reduced pressure, subjecting the vaporous conversion products of the process to 25 fractionation, whereby their insufficiently converted components are condensed as reflux condensate and separated into selected relatively low-boiling and high-boiling fractions, subjecting fractionated vapors of the desired end-boiling point to condensation, collecting the resulting distillate, returning said selected low-boiling 30 fractions of the reflux condensate to the heating coil for further conversion, together with said low-boiling fractions of the charging stock, and subjecting said selected high-boiling fractions of the charging stock and said high-boiling fractions of the reflux condensate to conversion within the same system under less severe conversion 35 conditions than those to which said low-boiling fractions of the charging stock and low-boiling fractions of the reflux condensate are subjected.

4. A process as claimed in claim 3 wherein the stream of highly heated products from said heating coil are cooled sufficiently to retard their excessive further conversion by indirect heat exchange with hydrocarbon oil charging stock for the process, whereby to furnish heat for said fractional distillation of the charging stock.

5. A process as claimed in claim 3 wherein the stream of highly heated products from said heating coil are cooled sufficiently to retard their excessive further conversion by indirect heat exchange with hydrocarbon oil charging stock for the process, whereby to furnish heat for said fractional distillation of the charging stock, and wherein said selected high-boiling fractions of the charging stock are subjected to independently controlled conversion conditions of elevated temperature and superatmospheric pressure in a separate heating coil, the heated products from 70 said separate heating coil and said high-boiling

fractions of the reflux condensate being supplied to the reaction chamber.

6. A process as claimed in claim 3 wherein the stream of highly heated products from said heating coil are cooled sufficiently to retard their excessive further conversion by indirect heat exchange with hydrocarbon oil charging stock for the process, whereby to furnish heat for said fractional distillation of the charging stock, and wherein said high-boiling fractions of the reflux 10 condensate are subjected to independently controlled conversion conditions of elevated temperature and superatmospheric pressure in a separate heating coil, the heated products from said separate heating coil and said selected high-boiling fractions of the charging stock being supplied to the reaction chamber.

7. A process as claimed in claim 3 wherein the stream of highly heated products from said heating coil are cooled sufficiently to retard their excessive further conversion by indirect heat exchange with hydrocarbon oil charging stock for the process, whereby to furnish heat for said fractional distillation of the charging stock, and wherein said selected high-boiling fractions of the 15 charging stock and said high-boiling fractions of the reflux condensate are subjected to independently controlled conversion conditions of elevated temperature and superatmospheric pressure in a separate heating coil, the heated products from said separate heating coil and said selected high-boiling fractions of the charging stock being supplied to the reaction chamber.

8. A process as claimed in claim 3 wherein said selected high-boiling fractions of the charging stock are subjected to independently controlled conversion conditions of elevated temperature and superatmospheric pressure in a separate heating coil, the heated products from said separate heating coil and the high-boiling fractions of the reflux condensate being supplied to said 30 reaction chamber.

9. A process as claimed in claim 3 wherein the high-boiling fractions of the reflux condensate are subjected to independently controlled conversion conditions of elevated temperature and superatmospheric pressure in a separate heating coil, the heated products from said separate heating coil and said high-boiling fractions of the charging stock being supplied to the reaction 45 chamber.

10. A process as claimed in claim 3 wherein said selected high-boiling fractions of the charging stock and the high-boiling fractions of the reflux condensate are subjected to independently controlled conversion conditions of elevated temperature and superatmospheric pressure in a separate heating coil, the heated products from 50 which are supplied to the reaction chamber.

11. A process as claimed in claim 3 wherein said selected high-boiling fractions of the charging stock and the high-boiling fractions of the reflux condensate are commingled with the highly heated products from said heating coil and subjected therewith to further conversion in the reaction chamber.

12. A process for producing anti-knock motor fuel from crude petroleum containing natural gasoline which comprises subjecting the crude to fractional distillation and separating selected relatively low-boiling and high-boiling fractions 70 therefrom, supplying the selected low-boiling fractions, including the low anti-knock gasoline components of the crude, to a heating coil, wherein they are subjected to conversion conditions of elevated temperature and superatmospheric pres- 75

sure adequate to enhance the anti-knock value of said gasoline components, introducing the products from said heating coil into an enlarged reaction chamber also maintained at superatmospheric pressure and at a conversion temperature, introducing said selected high-boiling fractions of the crude into said reaction chamber wherein they are subjected to conversion, withdrawing vaporous and liquid conversion products from the reaction chamber, subjecting the vaporous conversion products of the process to fractionation, whereby their insufficiently converted components are condensed as reflux condensate and separated into selected relatively low-boiling and high-boiling fractions, subjecting fractionated vapors of the desired end-boiling point to condensation, collecting the resulting distillate, returning said selected low-boiling fractions of the reflux condensate to the heating coil for further conversion, together with said low-boiling fractions of the crude, and returning said high-boiling fractions of the reflux condensate to the reaction chamber for further conversion.

13. The process as defined in claim 12 further characterized in that said high-boiling fractions of the reflux condensate are subjected to independently controlled conversion conditions of elevated temperature and superatmospheric pressure in a separate heating coil prior to their introduction to the reaction chamber.

14. The process as defined in claim 12 further characterized in that said high-boiling fractions of the crude are subjected to independently controlled conversion conditions of elevated temperature and superatmospheric pressure in a separate heating coil prior to their introduction to the reaction chamber.

15. The process as defined in claim 12 further characterized in that said high-boiling fractions of the reflux condensate and of the crude are subjected to independently controlled conversion conditions of elevated temperature and

superatmospheric pressure in a separate heating coil prior to their introduction to the reaction chamber.

16. A process for producing anti-knock motor fuel from crude petroleum containing natural gasoline which comprises subjecting the crude to fractional distillation and separating selected relatively low-boiling and high-boiling fractions therefrom, supplying the selected low-boiling fractions, including the low anti-knock gasoline components of the crude, to a heating coil wherein they are subjected to conversion conditions of elevated temperature and superatmospheric pressure adequate to enhance the anti-knock value of said gasoline components, introducing the products from said heating coil into an enlarged reaction chamber also maintained at superatmospheric pressure and at a conversion temperature, withdrawing vaporous and liquid conversion products from the reaction chamber, subjecting the latter to further vaporization at substantially reduced pressure, subjecting the vaporous conversion products of the process to fractionation, whereby their insufficiently converted components are condensed as reflux condensate and separated into selected relatively low-boiling and high-boiling fractions, subjecting fractionated vapors of the desired end-boiling point to condensation, collecting the resulting distillate, returning said selected low-boiling fractions of the reflux condensate to the heating coil for further conversion, together with said low-boiling fractions of the crude, and subjecting said selected high-boiling fractions of the crude and said high-boiling fractions of the reflux condensate to conversion within the same system under less severe conversion conditions than those to which said low-boiling fractions of the crude and low-boiling fractions of the reflux condensate are subjected.

JACQUE C. MORRELL.
